UNITED STATES PATENT OFFICE.

HARRY VISSERING, OF CHICAGO, ILLINOIS, ASSIGNOR TO HARRY VISSERING AND COMPANY, OF CHICAGO, ILLINOIS, A CORPORATION OF ILLINOIS.

TRAP FOR SANDER DEVICES.

1,109,093.

Specification of Letters Patent.

Patented Sept. 1, 1914.

Application led February 17, 1910, Serial No. 544,434. Renewed July 2, 1914. Serial No. 848,696.

To all whom it may concern:

Be it known that I, HARRY VISSERING, a citizen of the United States, and a resident of Chicago, in the county of Cook and State 5 of Illinois, have invented certain new and useful Improvements in Traps for Sander Devices, of which the following is a specification.

My present invention relates especially to 10 sanding apparatus for locomotives and more particularly to devices of this class in the operation of which air or other fluid pressure is employable rather than gravity alone.

15 This invention contemplates the provision of an improved sand trap, and improved fluid pressure delivery connections for such trap for use in connection with sanding apparatus.

20 The primary objects of my invention are the provision of a trap so improved and constructed as to be less susceptible to the grinding action of the whirling sand blast on the interior of the trap and so of substantially longer life in service, whereby the 25 cost and inconvenience of replacement and repair may be saved; the provision of a trap having an improved arrangement of passages and connections whereby the whirling motion of the sand is largely overcome, and the passage of sand therefrom, obstructing and injuring the apparatus and rendering it less efficient, if not inoperative, is avoided; the provision of means whereby 30 the wearing parts may be readily renewed if necessary; and the provision of means whereby the trap may be readily cleaned.

35 My invention also has for its objects the provision of an improved method of forming the resistant lining above referred to by pouring molten metal around temporary cores inserted into the trap, together with other objects which will be hereinafter defined.

40 In the attainment of the objects stated as well as certain further advantages to be below disclosed, I have provided the construction illustrated in the accompanying drawings, wherein—

45 Figure 1 is a skeleton outline of a side elevation of a steam railway engine or locomotive, equipped with a track sanding device employing my improvements; Fig. 2 is an enlarged perspective view of the ex-

terior of the sand box and trap of Fig. 1 55 and the operative connections therefor, illustrating the manner in which the trap is supported by the sand box of the locomotive; Fig. 3 is an enlarged sectional view of the forward half of the said trap taken on the 60 median line of Fig. 2, illustrating the internal arrangement of the passages, connections, ejector nozzle and resistant lining employed therein; Figs. 4 and 5 are further enlarged sectional views of the said trap 65 illustrative of certain means employed by me in my preferred method of forming the resistant lining in said trap, Fig. 4 being taken on the line IV—IV of Fig. 5, and Fig. 5 being taken on the line V—V of 70 Fig. 4.

Referring now more particularly to Figs. 1 and 2 of the drawing, it will be observed that I here illustrate diagrammatically the application of my invention, which though 75 of utility elsewhere I find peculiarly available in connection with the present general design of track sander construction. This comprises as here shown a compressed air reservoir, 10, from which a conduit pipe 11 80 leads to the engineer's cab where a controlling valve 12 is operable to admit the passage of the air supply through the conduit 13 leading to the sand trap 14 and by a branch 15, to the interior of the sand box 85 16, a delivery pipe 17 leading from said trap 14 to the ejector device 18 arranged adjacent the point of contact of the driver wheel with the rail. The trap 14 is attached to the sand box by bolts 19 passed 90 through the holes, 20 and short delivery pipes 21, 22 are inserted in said inlets at the ends of the passages 23 and 24. The pipe 21 is normally open toward the interior of the sand box 16 for the influx of sand into 95 the trap 14, but the pipe 22 is normally closed by a valve 25 having projecting arms 26 for breaking up the sand should it become caked or compacted in the box, 16. The valve 25 is operable from the cab 100 through a hand lever with an extension rod 27, said valve 25 being mounted at one end of a rocking lever supported upon a bar, 28, the opposite end of said rocking lever having a downwardly extending projection, 105 29, engaging one end of a link 30 to the other end of which the extension rod 27 is connected.

The body of the trap 14 is provided with a passage 23 open at both sides of the body for a purpose to be below described and suitable connections at the outlet 24 to receive the said delivery pipe 17, and at the inlet 31 to receive the fluid pressure supply pipe 13. Communicating with the inlet 31 by the passage 32 is a secondary trap or chamber 33 open at the top but normally closed 5 from the atmosphere by a plug 34 and communicating with the sand inlet 23 by means of a nozzle 35 threaded into a passage 52 (Fig. 5).

It is generally understood by those versed 15 in the operation and care of apparatus to which my invention relates, that traps for sander devices of the character referred to herein have required much care, continual repairs and repeated replacement, and therefore have been unavoidably expensive in this 20 that firstly, owing to the whirling and grinding action of the sand entering the trap from the connection 21, when acted upon by the blast of compressed air from the connection 31 as heretofore arranged, and a 25 backward suction upon closing the controlling valve 12 tending to draw sand into the pipe 13, the sand rapidly wears away the air nozzle 35, enlarging and rendering unsymmetrical the orifice thereof, lessening efficiency 30 of the device in operation and by permitting undue admission of air causing unnecessary expense, drain of the air supply, and load on the air compressor; and, secondly, when the sander is at rest, sand from 35 the connection 21, by reason of the jarring sustained by the engine while running, sifts into the pipe 13, thence to the valve 12 and at length through the tank into the compressor 40 in pneumatically operated apparatus, or into the boiler in steam operated sanders, by virtue of the circumstance that the connection 21 is usually level with or below the nozzle 35.

For the purpose of overcoming the disadvantages above specified and attaining certain further benefits, I have provided the passage 36 and 36^a with an insert comprising upper and lower portions 37, 37^a, preferably filling the cored body portion 38 of the trap, such insert being of comparatively soft material which is not so susceptible to the abrasive action of the sand blast, as is the relatively hard metal of the body of the 55 trap 14. In practice I have found that lead is the material best adapted for the purpose stated, though rubber of varying compositions and other somewhat yieldingly resistant materials may be used advantageously 60 and are comprised within the spirit of my invention and intended to be covered by my claims. The use of the soft metal lining referred to accomplishes the desired object of tending to overcome the wearing action 65 of the blast on the passage 38 and nozzle 35

and to eliminate the whirling motion of such sand, due to the fact that the soft metal lining roughens in raised points rather than in grooves under the action of the sand. The removable cap 39 is likewise provided on its 70 interior face with an insert 39^a having dovetailed connection therewith and where desirable the passage 40 may likewise be provided with a lining made according to my present method as below described or one 75 in the form of an inserted pipe as illustrated in my copending application for Letters Patent No. 491,945.

On viewing Fig. 3 particularly, it will be observed that to prevent sand entering the 80 trap through the connection 23 from sifting through the nozzle 35 into the pipe 13, as well as for the further purpose below referred to, I have arranged the nozzle 35 at an angle and in such a manner that the air 85 blast entering the trap therethrough will impinge angularly upon the sand from above and blow it through the passages 36 and 40 and thence discharge it through the connection 24 into the delivery pipe 17, instead of mounting it in axial alinement with the passage 36 as has heretofore been the customary mode of construction wherein the air blast instead of impinging upon the mass of sand blows through it. From further inspection of Fig. 3, it will be observed 90 that in my present invention the nozzle 35 is inserted with the relatively large end 41 of the passage 42 toward the sand supply and the relatively small end 43 of such discharge directed toward the air supply connection. By this arrangement and location of the nozzle 35 I find that two primary advantages in addition to those above pointed out are attained; first, owing to the expansion of the air as it passes from the smaller part 43 of the passage 42 into the larger part 41 thereof a large part of the rebounding action of the sand is eliminated and consequently the minimum wear of the nozzle 35 100 takes place; and, second, that since the air supply is not used to overcome the inertia of a considerable weight of sand accumulated upon the discharge passage, it moves the sand with much greater rapidity, or, in 105 other words, the actuation of the device and hence the application of sand to the rails is materially accelerated and a materially smaller quantity of air is used. The screw plugs 34, 38, and 44, the latter one closing 110 the passage 23 to which an additional sand delivery pipe may be attached if desired, are provided not only for the purpose of inserting the nozzle, lining, etc., in place but also to facilitate the cleaning of the trap should 115 sand become compacted therein.

Referring now more particularly to Figs. 4 and 5 it will be observed that I here illustrate a method of forming in portion 38 of the trap body 14, the lining 37 having 120

a passage 36, which consists in inserting a tapered core plug 45 in the opening 46 of the passage 23, such plug 45 having cut out portion indicated in dotted lines at 47, (Fig. 4), adapted to receive the end indicated by the dotted lines at 48 (Fig. 5) of a tapered core plug 49 inserted in the opening 50 which in service is closed by the cap 39. The passages 40 and 52 being dammed in any suitable manner, molten metal is then poured around the core block 49 until the passage 38 is completely filled by the molten metal and the lining 37 completed. The plugs 49 and 45 respectively are then driven out, the passage 52 drilled, the passages 36 and 36^a reamed out as desired, and the nozzle 35 and the several plugs 34, 38 and 44 inserted in place.

In view of the foregoing description, it is believed that the method of construction and of operation of sander systems employing devices embodying my improvements will be fully understood by those who are skilled in the art to which my invention pertains without further explanation.

Having thus described my invention and illustrated its use, what I claim as new and desire to secure by Letters Patent is the following:

1. A trap comprising a relatively hard body portion having connections to a receptacle for material, a discharge passage 36 and a connecting passage 36^a, and a relatively soft metal lining in said passage 36^a.

2. A trap comprising a body portion having a passage 36^a and a lead lining in said passage.

3. A trap comprising a body portion having passages 36 and 36^a and an integral soft lining in said passages.

4. A trap having a connection to a receptacle for material, a connection to a source of fluid pressure, and a nozzle, said nozzle being arranged above said material receptacle connection, and having a relatively large orifice toward the material connection and a relatively small opening toward the fluid pressure connection.

5. A trap having a connection to a receptacle for material, a connection to a source of fluid pressure, and a downwardly discharging blast nozzle between said connection to the receptacle for material and fluid pressure supply, said nozzle being located above said fluid pressure connection, and having a relatively large orifice toward the material connection and a relatively small opening toward the fluid pressure connection.

6. A trap having a connection to a receptacle for material, a connection to a source of fluid pressure, and a downwardly discharging blast nozzle between said connection to the receptacle for material and fluid pressure supply, and having a relatively

large orifice toward the material connection and a relatively small opening toward the fluid pressure connection.

7. A trap having a connection to a receptacle for material, a connection to a source of fluid pressure, and a blast nozzle disposed at an angle to both the perpendicular and the horizontal and arranged between said connection to the receptacle for material and fluid pressure supply and above the point of introduction into the trap of said material connection for downward discharge upon the surface of the material, whereby substantially the entire surface of the sand may be subjected to the force of the blast at an acute angle to such surface directed thereupon.

8. A trap having a connection to a receptacle for material, a connection to a source of fluid pressure, the discharge orifice of said fluid pressure connection being located above the point of introduction into the trap of said material receptacle connection, and a connection to the atmosphere above said material receptacle connection so arranged that said fluid pressure connection may be cleaned without disturbance of the fluid pressure connection or material lying in the trap.

9. A trap comprising a body portion having a connection to a receptacle for material, a connection to a source of fluid pressure, a passage between said connections, a nozzle in said passages, a chamber above said nozzle and above the connection to the material receptacle.

10. A trap comprising a body portion having a connection to a receptacle for material, a connection to a source of fluid pressure having an outlet thereabove, a passage between said connections, and a secondary trap above said passage.

11. A trap comprising a body portion having a connection to a receptacle for material, a connection to a source of fluid pressure, a passage between said connections, and a chamber above said passage and above the connection to the material receptacle.

12. A trap comprising a body portion having a connection to a receptacle for material, a connection to a source of fluid pressure, and a nozzle between said connections, said nozzle having a relatively large orifice toward said receptacle connection and a relatively small orifice toward said pressure supply connection.

13. A trap comprising a body portion having a connection to a receptacle for material, a connection to a source of fluid pressure, a passage between said connections, and a nozzle between said connections, said nozzle having a relatively large orifice toward said receptacle connection, and a relatively small orifice toward said pressure supply connection.

14. A trap comprising a body portion hav-

- ing a connection to a receptacle for material, a connection 31 to a source of fluid pressure, a passage 52, and a secondary trap 33 between said passage and connection.
15. A trap comprising a body portion having a connection to a receptacle for material, a connection 31 to a source of fluid pressure, a passage 52 and a secondary trap 33 between said passage and connection open to the atmosphere whereby said chamber may be cleaned.
16. A trap having a connection to a sand box, a connection to a source of fluid pressure, and a secondary trap located above the connection to the sand box, for preventing sand from passing into the fluid pressure connection.
17. A trap having a connection to a receptacle for material, a connection to a source of fluid pressure, and an angularly disposed nozzle located above said fluid pressure connection having a passage with a relatively large opening toward the material connection and a relatively small opening toward the fluid pressure connection.
18. A trap having a connection to a receptacle for material, a connection to a source of fluid pressure, and a nozzle disposed at an angle to the horizontal and having a passage with a relatively large opening toward the material connection and a relatively small opening toward the fluid pressure connection.
19. In track sanding apparatus, the combination of a source of fluid pressure; a receptacle for sand; a sand discharge pipe; a conduit from the source of fluid pressure to said receptacle; means for normally preventing the flow of material from the receptacle to the discharge pipe, having located on one side thereof an ejector device for said fluid pressure connection with its orifice downwardly directed and on the other side thereof a connection to said discharge pipe; and controlling means between said source of fluid pressure and said restraining means; said controlling means being in connection with the fluid pressure supply and said receptacle for material, and arranged to admit fluid pressure to the ejector device in one position and render it inoperative when in another position, the sand discharge pipe being in communication through the restraining means with the pressure supply connection.
20. The method of sanding railroad tracks which consists in feeding the sand against a restraining means, and thereafter downwardly directing a blast of air through a nozzle having an outlet larger than its inlet and arranged away from the surface of the sand, directly upon the surface of the sand at an angle to both the horizontal and the perpendicular.
21. The method of ejecting powder which consists in feeding it by gravity against a restraining means and subjecting the surface of the powder to the direct impingement at an angle to both the horizontal and to the perpendicular of a downwardly expanding blast of compressed fluid forced through a nozzle having an outlet larger than its inlet and arranged away from the surface of the powder.
22. The method of ejecting powder which consists in feeding it against a restraining means and subjecting the surface of the powder to the direct impingement at an angle to both the horizontal and to the perpendicular of a downwardly expanding blast of compressed fluid forced through a nozzle having an outlet larger than its inlet and arranged away from the surface of the powder.
23. A trap comprising a body portion having a connection to a receptacle for material, a connection to a source of fluid pressure, and a nozzle between said connections, said nozzle being provided with a passage having a small orifice toward said pressure supply connection and a larger substantially cylindrical orifice toward said receptacle connection.
24. A trap having a connection to a receptacle for material, a connection to a source of fluid pressure, and a nozzle, said nozzle being arranged above said material connection and said fluid pressure connection being arranged below said material connection.
25. A trap having a connection to a receptacle for material, a connection to a source of fluid pressure, and a downwardly discharging nozzle, said nozzle being arranged above said material connection and said fluid pressure connection being arranged below said material connection.
26. A trap having a connection to a receptacle for material, a connection to a source of fluid pressure, and a nozzle, said nozzle being arranged above said material connection and having a relatively large orifice toward the material connection and a relatively small opening toward the fluid pressure connection, and said fluid pressure connection being arranged below said material connection.
27. A trap having a connection to a receptacle for material, a connection to a source of fluid pressure, and a nozzle, said nozzle being arranged above the point where said material connection enters the trap.
28. A trap having a connection to a receptacle for material, a connection to a source of fluid pressure, and a blast nozzle between said connection to the receptacle for material and the fluid pressure supply arranged to discharge upon the surface of the material at an acute angle thereto, and discharge means for the trap, said nozzle and discharge means being arranged at an angle to both the perpendicular and the horizontal and at substantially a right angle to each other.

29. A trap having a connection to a receptacle for material, a connection to a source of fluid pressure, and a blast nozzle between said connection to the receptacle for material and the fluid pressure supply arranged to discharge upon the surface of the material at an acute angle thereto, and discharge means for the trap, said nozzle and discharge means being arranged at substantially a right angle to each other, and said connection to the receptacle being arranged at an angle to both the perpendicular and the horizontal and at an angle to said nozzle and discharge means. 25
30. A trap having a connection to a receptacle for material, a connection to a source of fluid pressure, and a downwardly discharging blast nozzle between said connection to the receptacle for material and the fluid pressure supply arranged to discharge upon the surface of the material at an acute angle thereto, and upwardly disposed discharge means for the trap, said nozzle and discharge means being arranged at an angle to each other, and said connection to the receptacle being arranged at an angle to both the perpendicular and the horizontal and at an angle to said nozzle and discharge means. 30
- 35
31. A trap having a connection to a receptacle for material, a connection to a source of fluid pressure, and a downwardly discharging blast nozzle between said connection to the receptacle for material and the fluid pressure supply arranged to discharge upon the surface of the material at an acute angle thereto, and upwardly disposed discharge means for the trap, said nozzle and discharge means being arranged at an angle to each other, and said connection to the receptacle being arranged at an angle to both the perpendicular and the horizontal and at an angle to said nozzle and discharge means. 40
- 40

In testimony whereof I have hereunto signed my name in the presence of the two subscribed witnesses.
